UNITED STATES PATENT OFFICE.

BENJAMIN P. HAYES, OF KANSAS CITY, MISSOURI.

SPRING-WINDING MACHINE.

1,267,867.

Specification of Letters Patent. Patented May 28, 1918.

Application filed June 2, 1916. Serial No. 101,267.

To all whom it may concern:

Be it known that I, BENJAMIN P. HAYES, a citizen of the United States, residing at Kansas City, in the county of Jackson and State of Missouri, have invented certain new and useful Improvements in Spring-Winding Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to spring winding mechanism, and has for its object to provide a machine of this character whereby the diameter or flight of a spring may be varied by slight and simple adjustments and wherein means is provided for accommodating spring wires of different gage.

In accomplishing this object, I have provided details of structure hereinafter described and illustrated in the accompanying drawings, wherein:—

Fig. I is a perspective view of a spring winding machine constructed according to my invention.

Fig. II is a horizontal vertical section of the same.

Fig. III is a vertical section on the line III—III Fig. II.

Fig. IV is a detail perspective view particularly illustrating the winding points and adjusting mechanism.

Fig. V is a perspective view of a removable winding point.

Fig. VI is a sectional view on the line VI—VI Fig. II, showing the pivotally supported bearing of the winding shaft.

Referring more in detail to the drawings:—

I designates a machine embodying my invention comprising a base member 2, having end standards 3—4 thereon which revolvably support the converging winding spindles 5, 6 and 7.

The paired lower or base spindles 5—6 are revolvably mounted at their forward ends in bearings 3' in the standard 3 and at their opposite ends in bearings 4' in the standard 4, and are provided with pointed end portions 5'—6' that extend forwardly from the

bearings 3', and terminate adjacent each other and operate in the same axial plane.

The upper spindle 7, which I designate the pressure spindle as it tends to force the wire into a recess between other lower spindles 5—6, is provided with a removable point 7' and carried at its forward end in a block 8 that is slidably mounted in a slot 9 in the standard 3, and in a bearing 10 that is pivotally mounted in an opening 12 in the standard 4 by means of set screws 13, which are threaded through bosses 14 in the standard 4 and seat in sockets 15 on opposite sides of the bearing 10, so that the spindle may rock thereon and may be adjusted at its forward end toward or from the converging points of the lower spindles.

The means for adjusting the shaft 7 comprises a thumb screw 16 which is threaded through a cross bar 17 on the standard 3 and bears against the upper face of the block 8, which carries the shaft and is slidable in the slot 9.

Located beneath the block 8 at the base of the slot 9, is a socket 20, which extends downwardly within the bearings 3' and 80 seated therein is a coil spring 21, which yieldingly supports a pin 22 which extends from the socket and bears at its upper end against the block 8, so that by adjusting the screw 16 the bearing 8 may be raised or lowered to adjust the point 7' of the upper spindle toward or away from the lower spindle points.

The spindle 7 is extended outwardly from the bearing 10 and is provided at its end 90 with a crank 25 whereby it may be revolved to wind the spring, as will presently be described, and mounted on the said spindle between the standards is a bevel gear wheel 26 which meshes with like gears 27—28 on 95 the lower spindles 5—6 and whereby the lower spindles are rotated simultaneously with the upper spindle.

The tapered point 7' of the upper spindle is provided adjacent the said point with a 100 peripheral groove 29 within which the spring wire is fed and guided as it is rolled between the converging spindle points to form the spring convolutions.

In winding a spring, a straight piece of 105 spring wire of a gage to give the desired strength is fed between the converging points 5'—6'—7' through the guide groove

29 in the upper spindle, and the upper spindle is tightened thereagainst by adjusting the set screw, so that as the wire passes between the spindle points it will be bent 5 in the arc of a circle and by continued winding will be formed in convolutions which may be given any desired spacing or flight by adjusting a guide arm 30 carried by a block 31 which is slidably mounted on a 10 stub shaft 32 extending forwardly from the standard 3 parallel with the shaft 7; the arm 30 being held in any adjusted position by a set screw 35 and the block being held to its adjusted position on the shaft 32 by a 15 set screw 36.

In order that spring wire of different diameter or gage may be used, it is necessary that the upper spindle, which is provided with the guide groove 29, be made removable, so that a spindle containing a 20 groove of different width or depth may be inserted. This is done by providing the spindle with an internally threaded end socket 40 and the point 7' with a shank 42, 25 which may be threaded into the socket and has a shoulder 43 for seating against a corresponding shoulder 44 on the winding spindle.

I also provide a guard 46 which is attached to the rear standard 4 and closely overlies the driving gears as a protection to the operator of the machine.

Presuming the parts to be so constructed, it will be seen that a spring of a desired 35 diameter may be formed by adjusting the grooved point toward or from the lower points to give the spring a greater or smaller radius of curvature, and that the flight of the spring convolutions may be 40 spaced by shifting the guide arm on the shaft so that as the wire is wound through the spindles it engages therewith and is curved outwardly thereby; the flight of the convolution corresponding to the degree of curvature given the wire as it comes from 45 between the spindles.

It is also apparent that the points of the winding spindle may be removed, so that one provided with a groove of a desired 50 curvature may be inserted to accommodate small or large wire and that the spring convolutions may be closed, or spread to make either a compression or extension spring.

Having thus described my invention, what 55 I claim as new therein and desire to secure by Letters-Patent, is:—

1. A spring winding machine comprising base spindles having upwardly-inclined, 60 converging axes and terminating in conical points, a pressure spindle rotatably mounted on an axis equidistant from those of the base spindles and at an angle convergent relative thereto, the pressure spindle having 65 a tapered point lying between the points of

the base spindles to form a tortuous transverse path therebetween, and said tapered point having a circumferential groove adjacent its smaller end for retaining a spring wire against movement along the spindles. 70

2. A spring winding machine comprising base spindles having upwardly-inclined, converging axes and terminating in conical points, a pressure spindle rotatably mounted in an axis equidistant from those of the base spindles and at an angle convergent relative thereto, the pressure spindle having a tapered point lying between the points of the base spindles to form a tortuous transverse path therebetween, said tapered point 75 having a circumferential groove adjacent its smaller end for retaining a spring wire against movement along the spindles, and means for rotating the paired spindles and the pressure spindle in clockwise and counter-clockwise directions respectively. 80

3. A spring winding machine comprising base spindles having upwardly-inclined, converging axes and terminating in conical points, a pressure spindle rotatably mounted on an axis equidistant from those of the base spindles and at an angle convergent relative thereto, the pressure spindle having a tapered point lying between the points of the base spindles to form a tortuous transverse path therebetween, and said tapered point 90 having a circumferential groove adjacent its smaller end for retaining a spring wire against movement along the spindles, gear wheels on the base spindles, a gear 95 wheel on the pressure spindle meshing with the gear wheels on both of the base spindles, and means for rotating the pressure spindle.

4. A spring winding machine comprising a base member having spaced standards 105 thereon, a pair of conically pointed spindles revolvably carried by said standards with the smaller ends extending in the same direction, a spindle revolvably mounted above said paired spindles with its axis 110 in a plane that would bisect the axial plane of the paired spindles, and having a conical point closely overlying the conical points of the first named spindles, means for adjusting the last named spindle point toward 115 or from the first named points, means for simultaneously rotating the spindle points, so that a wire rolled therebetween will be continuously curved to form convolutions, and adjustable means for spacing said convolutions. 120

5. In a spring winding machine, the combination with a pair of conically pointed spindles placed with their smaller ends in the same direction, of a conically pointed 125 spindle, having its axis in a plane bisecting the axial plane of the paired spindles and revolvably supported near its pointed end in a slideable bearing, and at its opposite end in a pivotally supported bearing, and 130

means for rocking the single spindle in its pivotal mounting to adjust the pointed end thereof toward or from the pointed ends of the paired spindles for the purpose set forth.

6. In a spring winding machine, the combination with a pair of conically pointed spindles placed with their smaller ends in the same direction, of a conically pointed spindle, having its axis in a plane bisecting the axial plane of the paired spindles and revolubly supported near its pointed end

in a slidable bearing, and at its opposite end in a pivotally supported bearing, a spring pressed pin engaging the under face 15 of the adjustable spindle to urge it away from the lower spindle points and a screw bearing against the upper face of said slid-
able bearing for adjusting the same toward the paired spindle points for the purpose 20 set forth.

In testimony whereof I affix my signature.

BENJAMIN P. HAYES.
